UNITED STATES PATENT OFFICE.

GEORGE W. NIBBE, OF CHICAGO, ILLINOIS.

DERAILING DEVICE.

1,109,007.

Specification of Letters Patent.

Patented Sept. 1, 1914.

Application filed November 10, 1913. Serial No. 800,026.

To all whom it may concern:

Be it known that I, GEORGE W. NIBBE, a citizen of the United States, and a resident of Chicago, in the county of Cook and State of Illinois, have invented certain new and useful Improvements in Derailing Devices; and I do hereby declare that the following is a full, clear, and exact description thereof, reference being had to the accompanying 10 drawings, and to the letters of reference marked thereon, which form a part of this specification.

This invention relates to an improvement in derailing devices and consists of the matters hereinafter described and more particularly pointed out in the appended claims.

The railroad rails used by different roads, and even those used by the same road on different branches and in yards may vary 20 widely in weight and the different weights of rail vary in height, that is to say, in the distance from the top of the ball of the rail to the base flange which rests on the tie.

Derailing devices, as heretofore constructed, have been such that it has been necessary for each railroad to have a supply of derailing devices for each weight of rail used in its system. This is annoying and expensive and the object of the present invention is to provide a derailing device capable of such adjustment that it may be applied to rails of any of the several weights between the maximum and minimum limits now employed by railroads.

85 In the drawings, Figure 1 is a view representing in perspective one of my improved derailing devices applied to a rail, as it appears when looked at from a point beyond the outer side of the rail. Fig. 2 is a view 40 in side elevation of the derailing device with the lugs or ears, to which the derailing member is hinged, shown in vertical section. Fig. 3 is a view representing a vertical section through the derailing device in a 45 plane indicated by the line 3—3 of Fig. 2. Fig. 4 is a view representing a vertical section through the derailing device in a plane indicated by the line 4—4 of Fig. 2. Fig. 5 is a view similar to Fig. 3, except that the 50 parts of the derailing device are shown adjusted in a different relation in order to accommodate a rail of a different height. Fig. 6 is a perspective view of the shaft upon which the movable part of the derailing device is rotatably mounted.

55 Referring now to that embodiment of my

invention illustrated in the drawings, 10 indicates a rail attached to and supported upon ties 11 in the usual manner. The derailing device is applied to the rail at a 60 point between two ties where a channel 12 below the rail base is formed in the ballast or roadbed to provide space for the parts of the device which are located below the level of the rail base.

65 My improved derailing device includes the usual derailing block 13, which is carried by a rock arm 14; a supporting and attaching member 15 by means of which the device is attached to the rail and by which 70 the rock arm 14 is rotatively carried; and an operating link 16 which extends transversely under the rail in the usual manner.

75 The derailing block 13 is of any familiar or convenient construction and has a rail tread 17 which is inclined downwardly so as to merge at one end into the top surface of the rail in order to guide the tread of the wheel to the top of the block and has an upright flange 18 inclined diagonally across 80 said tread from its inner to its outer edge so constructed that it will catch the wheel flange and force said wheel as it rides upon said block to travel in a diagonal direction across the block from its inner edge to its 85 outer edge in such manner as to derail the wheel. The formation of said block is of no interest in the present invention as it may be of any approved or preferred construction known to those familiar with the art, so that 90 a further description of the same is unnecessary.

95 The attaching and supporting member 15 has an upright flange 19 adapted for engagement with the outer face of the web of the rail and provided with apertures for bolts by means of which it may be attached to the rail. Said supporting member also has a base flange 21 for engagement with the top face of the rail base flange. Said 100 supporting member is provided with longitudinally spaced lugs 22 in which is carried a non-rotative shaft 23 extending parallel to the rail 10 and constituting the member upon which the rock arm 14 connected to 105 the derailing block 13 is hinged. Each of said lugs 22 has a vertically elongated slot 24 of a width substantially equal to the diameter of the shaft 23. The vertical sides of said slot are provided with vertically 110 spaced notches or keyways 25 which are adapted to receive oppositely placed keys

26, 26^a fixed to the shaft 23. There are two pairs of such keys fixed to the shaft, one pair being placed near one end and one pair near the other end for engagement with the 5 slots 24 in the respective lugs 22.

In order to provide vertical adjustment of the shaft 23 at points as closely spaced together as possible without unduly diminishing the thickness of the keys 26, 26^a and 10 the width of the grooves or keyways 25 in which they are secured, I prefer to place the keys on opposite sides of a plane through a diameter of the shaft 23 and to arrange the keyways 25 on the opposite sides of the 15 slots 24 in staggered vertical relation. Manifestly, the shaft may be adjusted distances equal to half the vertical distance between the keyway notches in the grooves by reversing the shaft end for end, thus 20 bringing the keys on one side of the shaft into engagement with one of the keyways which was engaged in the first instance, and bringing the keys on the other side of the shaft into engagement with the keyways 25 next below those with which the shaft was engaged in the first instance. The arm 14 is provided with a bearing aperture 28 to receive the shaft 23 and said bearing aperture has on each side notches 29, so that the 30 shaft with its keys may be passed through the aperture in the arm 14 in assembling the device no matter which way the keys are disposed.

30 indicates horizontally spaced lugs on 35 the arm 14 which project downwardly below the level of the shaft 23, and which are provided with apertures for the reception of a pivot bolt or nut 31 by means of which the link 16 is operatively connected to said 40 arm 14. The longitudinal movement of the link 16, produced by suitable mechanism placed on the outside of the rail opposite the rail 10, operates to swing the arm 14 so as to apply or remove the block 13 to 45 or from the rail as desired, in the usual manner.

In order to lock the derailing device in 50 position, one of the lugs 22 is provided with a flange 34 having a vertically elongated slot 35 and the arm 14 is provided with a similar flange 36 placed adjacent to the flange 34 and having a like vertically elongated slot 37. The hasp of a lock passed through 55 said two slots will apparently lock the parts in such position as to rigidly hold the derailing block on the rail.

While in describing my invention, I have referred to certain details of mechanical construction and arrangement, it is to be understood that the invention is in no way limited thereto except as pointed out in the appended claims.

I claim as my invention:

1. In a derailing device, the combination 65 of a derailing block, means for operatively

supporting said derailing block for motion to and from derailing position, and adjusting means whereby said derailing device may be made to accommodate rails of different heights. 70

2. In a derailing device, the combination of a derailing block, means for rotatively supporting said derailing block for motion to and from derailing position, and means for vertically adjusting the axis about which 75 said block rotates to accommodate rails of different heights. 75

3. In a derailing device, the combination of a derailing block, a support therefor fixed in a position adjacent to a rail, means for operatively connecting said derailing block to said support for motion to and from derailing position, and adjusting means whereby said derailing device may be made to accommodate rails of different heights. 80

4. In a derailing device, the combination of a derailing block, an arm fixed thereto, means for rotatively attaching said arm in a position adjacent to a rail, and means for vertically adjusting the axis of rotation of 90 said arm to accommodate rails of different heights. 90

5. In a derailing device, the combination of a derailing block, a rock arm fixed thereto, a supporting member adapted to be attached to the rail, means whereby said rock arm is rotatively connected to said supporting member, and means for vertically adjusting the axis of rotation of said arm to accommodate rails of different heights. 95

6. In a derailing device, the combination of a derailing block, a rock arm fixed thereto, a supporting member adapted for attachment to the rail and provided with longitudinally spaced lugs, a non-rotative shaft carried by said lugs, said rock arm being rotatively mounted on said shaft, and means providing for the vertical adjustment of said shaft in said lugs to accommodate rails of different heights. 105

7. In a derailing device, the combination of a derailing block, a rock arm fixed thereto, a supporting member adapted for attachment to the rail and provided with longitudinally spaced lugs, a non-rotative shaft 115 supported in said lugs, said rock arm being rotatively mounted on said shaft, said lugs being provided with vertically elongated slots to receive said shaft, and said slots having vertically spaced notches on each side, and said shaft being provided with keys to engage said notches. 120

8. In a derailing device, the combination of a derailing block, a rock arm fixed thereto, a supporting member adapted for attachment to the rail, said supporting member being provided with longitudinally spaced lugs, a shaft carried by said lugs and upon which said arm is rotatively mounted, said lugs being provided with vertically elong- 125 130

gated slots of a width substantially equal to the diameter of said shaft, and the vertical edges of said slots being provided with vertically spaced keyways, the keyways on 5 one side of said slots being arranged in staggered relation with reference to the keyways on the other side of said slots, and said shaft being provided with oppositely disposed keys for engagement in the keyways 10 of said slots.

9. In a derailing device, the combination of a derailing block, a rock arm fixed thereto, a supporting member adapted for attachment to the rail, said supporting member being provided with longitudinally spaced lugs, a shaft carried by said lugs upon which said rock arm is rotatively mounted, said lugs being provided with vertically elongated slots of a width substantially equal to the diameter of said shaft 20

and the opposite vertical sides of said slots being provided with vertically spaced keyways, the keyways on one side of said slots being arranged in staggered relation with reference to the keyways on the other side 25 of said slots, said shaft being provided with oppositely disposed keys for engagement in the keyways of said slots, and said rock arm being provided with a bearing aperture adapted to receive said shaft and to permit 30 the passage of said keys in assembling the device.

In testimony, that I, claim the foregoing as my invention I affix my signature in the presence of two witnesses, this 7th day of 35 November A. D. 1913.

GEORGE W. NIBBE.
